MOP AND SQUEEGEE COMBINED

Walter J. Zimmerman, Punxsutawney, Pa.

Application July 19, 1948, Serial No. 39,457

1 Claim. (Cl. 15—121)

1

The present invention relates to so-called household cleaning implements and has more particular reference to a novel and improved cleaning device which lends itself for effective scrubbing and cleaning of flat smooth surfaces such as found on glass door panels, window panes, painted walls, floors, windshields, glass show cases and so on and so forth.

It will be seen, as the introductory statement of the invention explains, that I am aware that there are many and varied types and forms of household cleaning devices for general utility purposes and that it is common to provide a rectangular sponge rubber or equivalent block having handle means and that it is also common practice to employ in conjunction therewith a rubber wiper or squeegee to permit the brushing, scrubbing and wiping steps to be satisfactorily attained. In carrying out the principles of the present invention I provide a cleaning device which is the utmost in simplicity of construction in that it is compact and susceptible of ready manufacture, assembling and sale and is susceptible of attaining the wanted ends with certainty and expediency.

More specifically, novelty is predicated on a backing plate provided with a rigidly attached handle, a rubber or equivalent block fastened on the backing plate, and a simple squeegee on the backing plate with edge portions of the rubber wiper strips projecting beyond the adjacent edge portion of the pad or block.

Other objects and advantages will become more readily apparent from the following description and the accompanying illustrative drawings.

In the drawings:

Figure 1 is a perspective view of a hand-used cleaning device constructed in accordance with the principles of the present invention;

Figure 2 is a longitudinal sectional view taken centrally through the structure seen in Figure 1;

Figure 3 is a fragmentary view showing, somewhat diagrammatically, the structural elements utilized by me;

Figure 4 is a perspective view of the backing plate.

Referring now to the drawings by reference numerals and lead lines, it will be seen that the cleaning pad, which is used for brushing, scrubbing and other similar tasks, is a sponge rubber or equivalent block 6 of general rectangular form. Said pad may, of course, be made of synthetic or plastic stock or may be a common sponge.

The backing plate 7 is of an area considerably less than the area of the pad and is provided with spaced holes 8 to accommodate fasteners, hereinafter referred to. The pad 6 is glued or otherwise fastened to the backing plate 7 so that the principal marginal edge portions of the pad project beyond corresponding edge portions of said plate.

Numeral 9 denotes a hollow handle which has 10 a head 10 riveted or otherwise secured to the central portion of the backing plate. The offset end of the handle is attached to the plate so as to provide for satisfactory leverage and use. Also, the handle is preferably hollow to provide a 15 socket as shown in Figure 2 which may be employed to take care of an extension handle 11 seen in dotted lines.

The numerals 12 designate elongated duplicated strips of rubber or equivalent material 20 which constitute flexible wipers. These are superposed upon each other and also superimposed upon an edge portion of the backing plate and are secured thereto by an elongated cleat or strip 13 held in place by rivets, screws, or the 25 like 14. The strips 12 project beyond the forward edge of the block and function as a squeegee, as is obvious.

Briefly reviewing the subject matter it will be seen that it is characterized by a block-like 30 compressible pad of sponge rubber or equivalent material suitable for brushing, scrubbing and cleaning purposes, the same being attached to a flat, primarily rectangular backing plate, the backing plate serving as a mount or base for rubber strips, said rubber strips coating with a retaining cleat in defining a convenient squeegee. The squeegee is in a plane with the backing plate and projects beyond the adjacent forward or outer edge of the pad. The handle 9 may be 35 used in a manner evident from the drawings or it may be employed as a socket for an extension handle 11 as indicated by the dotted lines. It is at a satisfactory angle in relation to the pad, backing plate and squeegee to permit said parts to be effectively handled.

The cleaning device is compact, complete in 40 all respects, eliminates splashing, dripping and spattering which is so common when an ordinary bristle brush or the like is used for cleaning purposes. The handle is attached at the correct angle for use of either the pad or the squeegee means. The pad and squeegee units will fit in corners without smearing or splashing the surfaces adjoining the surfaces which are, 45 at the time, being cleaned.

The device may be constructed in such sizes as to adapt it for industrial as well as household purposes and requirements. It will be found handy and useful when employed in and around automotive service stations in that it will handily serve in cleaning windshields, washing cars, and for other chores. In the office it may be used to assist in cleaning and conditioning linoleums and similarly covered floors.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

A manually usable implement for household and industrial cleaning purposes comprising a substantially rectangular compressible pad, a correspondingly shaped flat rigid backing plate, of an area less than the area of said pad, secured atop said pad, all of the marginal edge portions of the pad extending beyond the corresponding marginal edge portions of the backing plate, a pair of relatively narrow rubber wiper strips superimposed upon each other and supported by the forward longitudinal edge portion of said backing plate, said strips being of lengths greater than the length of the backing plate and of lengths approximately equal to the length of the pad, the transverse end portions of said wiper strips projecting beyond the corresponding edge.

5 portions of the backing plate and partially overlying the adjacent portions of the top surface of the pad, a flat rigid cleat superimposed upon inward longitudinal edge portions of said wiper strips and secured to the wiper strips and the underlying longitudinal edge portion of the backing plate, remaining longitudinal edge portions of said wiper strips projecting beyond and overhanging the coacting marginal edge portion of said pad, said cleat being appreciably narrower than said wiper strips, the latter and said cleat being in a plane substantially parallel to the top surface of said pad, and a handle secured to said backing plate.

10 15 WALTER J. ZIMMERMAN.
